UNITED STATES PATENT OFFICE.

JOHN A. WHERRY, OF NEW ORLEANS, LOUISIANA.

COLLATING DEVICE FOR TYPEWRITERS AND ADDING-MACHINES.

1,836,454.

Specification of Letters Patent. Patented Apr. 13, 1920.

Application filed July 3, 1919. Serial No. 308,362.

To all whom it may concern:

Be it known that I, JOHN A. WHERRY, a citizen of the United States, residing at New Orleans, in the parish of Orleans and 5 State of Louisiana, have invented certain new and useful Improvements in Collating Devices for Typewriters and Adding-Machines; and I do hereby declare the following to be a full, clear, and exact description 10 of the invention, such as will enable others skilled in the art to which it appertains to make and use the same.

This invention relates to a collating device for typewriters and adding machines, and 15 particularly to adding machines without the typewriter features, wherein a revoluble platen is used for ledger posting and statement work. The invention is in the nature of an improvement on the invention dis- 20 closed and claimed in my co-pending application, Serial No. 294,775, filed May 5, 1919.

The primary object of the invention resides in the provision of a collating device on which the work sheets may be assembled 25 or collated and carried to the printing position on the typewriter or on the adding machine without disarrangement. Furthermore, it is an object of the invention to dispose the sheet clamping and alining members and the operating mechanism therefor in such manner that they will interfere as little as possible with the assembling or collating operations.

In the drawings:

35 Figure 1 is a front elevation, showing the sheet alining and clamping members at the left side of the figure in their lowered positions, and the sheet alining and clamping members at the right side of the figure in 40 their raised positions;

Fig. 2 is a rear elevation of the device with the parts in the positions illustrated in Fig. 1;

Fig. 3 is an end elevation with part of 45 the carriage cut away and with the sheet alining and clamping members lowered to the board;

Fig. 4 is an end elevation showing the sheet alining and clamping members raised 50 from the board;

Fig. 5 is a sectional view showing the sheet alining and clamping members lowered to the board;

Fig. 6 is a sectional view showing the 55 sheet alining and clamping members raised from the board;

Fig. 7 is a perspective view of one of the angular supporting members, showing the sheet alining and clamping members and the supporting members therefor;

60

Fig. 8 is an end elevation of the portion of the device illustrated in Fig. 7, showing the sheet alining and clamping members raised from the board;

65

Fig. 9 is a similar view showing the uppermost of the sheet alining and clamping members raised and the remaining members lowered;

65

Fig. 10 is a detail sectional view illustrating the formation of the sheet alining and 70 clamping members; and

Figs. 11 and 12 are detail perspective views illustrating the milling of the upper and lower surfaces of the sheet alining and 75 clamping members.

A portion of the typewriter which includes a platen 1 and a carriage 2, is illustrated in the drawings, and my invention is shown as mounted on the carriage ends. The device comprises a collating board 3, which 80 is supported on the carriage ends by standards 4 and 5, these standards being struck from the material of the board at the side edges thereof and being secured at 6 to the carriage ends. The board itself is provided with a pair of parallel elongated openings or slots 7, which are arranged adjacent to the side edges of the board. A series of three slots 8, 9 and 10, is arranged adjacent to each of the slots 7, the slot 8 in each case 90 communicating with the adjacent slot 7, and the slots 9 and 10 being isolated therefrom and from each other.

On the rear face of the board 3 adjacent to each of the slots, an angular supporting 95 member 11 is secured by suitable fasteners 12, one web 13 of each of the supporting members sliding over against the rear face of the board and the other web 14 extending at right angles thereto. This web 14 is re-

95

cessed, as shown in Fig. 6 of the drawing, and is provided with a bar 15, which is secured to the web at the ends thereof for a purpose which will later appear. Sheet alining and clamping members 16, 17 and 18 are 100 mounted on the board and have sheet en-

gaging portions lying parallel with the front face of the board and in superposed relation to each other. The engaging faces of these sheet engaging portions are milled as 110

at 19, so as to securely clamp the sheets in place. These sheet alining and clamping

members are of angular form and have webs 20, 21 and 22, which extend through the slots 7 in the board. A series of springs 23 are attached to the webs 20, 21 and 22 of the sheet alining and clamping members and to adjustable bolts 24, which pass through the support 15. The tendency of these springs is to normally draw the sheet engaging portions toward the board into their 10 clamping positions, and the tension of the springs may be, of course, adjusted at will by the adjustment of the bolts 24. The movement of the sheet alining and clamping members with relation to the collating board 15 is at right angles thereto, and this movement is controlled by a pair of guide screws 25, which are secured to the portion 26 of the web 14 of each angular supporting member. These screws 25 extend through slots 27 in 20 the webs 20, 21 and 22 and thus act as guides.

Mounted on each of the webs 13 of the angular supporting members 11, is a series of slides 28, 29 and 30, the slides being 25 adapted to move longitudinally of the web, and being guided in their movement by screws 31, which extend through slots 32 in the slides and are secured to the web 13. Cam rods 33, 34 and 35 are secured to and 30 extend transversely of the slots 28, 29 and 30. These cam rods extend beyond the innermost slide 28 and into diagonally arranged cam slots 36, in the webs 20, 21 and 22 of the adjacent sheet alining and clamping 35 members, which cam slots are provided with depressions or recesses 37, for the reception of the cam rods 33, 34 and 35.

Operating handles 38 extend through the slots 8, 9 and 10 in the collating board 3 40 and are secured to the slides 28, 29 and 30, so that the latter may be moved longitudinally of the web.

In operation, assuming that the parts are 45 in the positions illustrated, in Fig. 5, for instance, that is to say, the sheet alining and clamping members are lowered to the board, the said members may be individually raised from the board by pulling upwardly on the proper operating handle 38. The 50 downward movement of each of these handles causes the movement of one of the slides 28, 29 or 30, and as a result, causes the cam rods, which are secured to the particular slide to move in the slots 36. Inasmuch as the cam rods are fixed with relation to the web 13, so far as any movement 55 at right angles thereto is concerned, the sheet alining and clamping members will be moved away from the board by the relative 60 movement between the cam rods and the cam slots. Of course, this movement of the sheet alining and clamping members will take place in opposition to the springs 23, and when each of the said sheet alining and 65 clamping members reaches the extent of its

movement, it will be locked in said position by the passage of the cam rods into the recesses 37 in the cam slots and will be held in such a position by the springs 23 until properly released. Of course, the sheet alining and clamping members may then be moved toward the board by the opposite movement of the handles 38, that is to say, they may be moved into their clamping or operative positions.

It will be appreciated from the above description that the sheet alining and clamping members may be raised individually, so that the collating operation will be greatly facilitated and consequently the chance of 80 displacement of the sheets will be reduced to a minimum. Furthermore, the location of the operating means on the rear of the collating board facilitates the collating, since it renders the face of the board particularly free.

As above stated, the sheet alining and clamping members may be moved individually to and away from the collating board, but it is to be realized that by raising the 90 lowermost of said members, the other two will be raised, and by raising the intermediate of said members, the uppermost member will be raised.

It will be noted that the slides 28 and 29 are provided with screws 100, which upon the downward pressure on the handle, which is indicated at 101 in Fig. 1, causes the simultaneous raising of the sheet clamping and alining members.

What I claim is:

1. In a collating device, the combination with a board, of sheet alining and clamping members mounted thereon in superposed relation, said members comprising sheet engaging portions and webs which extend through the board, means connected to the webs for normally drawing said sheet engaging portions toward the board, means for raising said portions away from the board, and means for maintaining said portions in their raised positions.

2. In a collating device, the combination with a board, of angular sheet alining and clamping members having sheet engaging portions disposed in superposed relation on the front of the board and having webs extending through the board and resilient means attached to said webs for normally drawing the sheet clamping portions toward the board.

3. In a collating device, the combination with a board, of angular sheet alining and clamping members having sheet engaging portions disposed in superposed relation on the front of the board and having webs extending through the board, resilient means attached to said webs for normally drawing the sheet clamping portions toward the board, and means for raising the sheet

- clamping and alining members from the board individually.
4. In a collating device, the combination with a board, of angular sheet alining and clamping members having sheet engaging portions disposed in superposed relation on the front of the board and having webs extending through the board, resilient means attached to said webs for normally drawing the sheet clamping portions toward the board, means for raising the sheet clamping and alining members from the board individually, and means for maintaining said members in their raised positions.
5. In a collating device, the combination with a board, of angular sheet alining and clamping means mounted on the rear of the board extending through the same and having sheet engaging portions located at the front of the board for alining, collating and clamping work sheets while the ends of said sheets are located between the feed rollers and the platen of the typewriter, and means on the rear of the board for normally drawing said portions toward the board.
6. In a collating device, the combination with a board, of angular sheet alining and clamping means mounted on the rear of the board extending through the same and having sheet engaging portions located at the front of the board for alining, collating and clamping work sheets while the ends of said sheets are located between the feed rollers and the platen of the typewriter, means on the rear of the board for normally drawing said portions toward the board, and means for raising the members individually.
7. In a collating device, the combination with a board, of angular sheet alining and clamping means mounted on the rear of the board extending through the same and having sheet engaging portions located at the front of the board for alining, collating and clamping work sheets while the ends of said sheets are located between the feed rollers and the platen of the typewriter, means on the rear of the board for normally drawing said portions toward the board, means for raising the members individually, and means for maintaining said members in their raised positions.
8. A collating device, comprising a board, of angular sheet alining and clamping mem-
- bers mounted on the rear of the board, extending through the same and having sheet engaging portions arranged in superposed relation on the front face of the board, resilient means for normally drawing the said portions toward the board, and means for varying the tension of said resilient means.
9. A collating device comprising a board, angular supporting members mounted on the rear of said board, angular sheet alining and clamping members mounted on said supporting members and having cam slots therein, movable cams carried by the supporting members and extending through said slots, means for actuating the cams to move the sheet alining and clamping members away from the board, and resilient means for returning said members to their original positions.
10. A collating device comprising a board, angular supporting members mounted on the rear thereof, angular sheet alining and clamping members slidably mounted on said supporting members and extending through the board, means for causing the last mentioned members to slide on the first mentioned members in one direction to raise the same from the board, and means for locking the clamping members in their raised positions.
11. A collating device comprising a board, angular supporting members mounted on the rear thereof, angular sheet alining and clamping members slidably mounted on said supporting members and extending through the board, means for causing the last mentioned members to slide on the first mentioned members in one direction to raise the same from the board, means for locking the clamping members in their raised positions, and means for returning the clamping members to their initial positions.
12. A collating device comprising a board, angular sheet alining and clamping members having sheet engaging portions disposed in superposed relation on the front of the board and having webs extending through the board to the back thereof, means for selectively raising said sheet engaging portions, and means for simultaneously raising said portions.
- In testimony whereof I affix my signature.
- JOHN A. WHERRY.
